UNITED STATES PATENT OFFICE.

WILLIAM P. SCHLINGER AND GEORGE R. PARANTEAU, OF OXNARD, CALIFORNIA.

SUCKER-ROD ELEVATOR.

Application filed June 23, 1924. Serial No. 721,750.

To all whom it may concern:

Be it known that we, WILLIAM P. SCHLINGER and GEORGE R. PARANTEAU, citizens of the United States, residing at Oxnard, in the county of Ventura and State of California, have invented a new and useful Sucker-Rod Elevator, of which the following is a specification.

This invention relates to rod elevators such as are employed in the handling of drill rods, sucker rods, tubing or casing in the construction and operation of wells such as oil wells.

An object of the present invention is to provide a rod elevator with jaws movable to and from a position closed around a rod in the elevator which jaws in moving to the open position move in a direction opposed to the weight of the rod supported upon the elevator so that the weight of such rod will normally apply the force tending to maintain the jaws of the elevator in the closed position.

Another object of the invention is to provide an elevator with jaws adapted to form a closure for the elevator, which jaws are pivoted to move about a horizontal axis in their opening and closing operations and in which the jaws pivot upwardly from the closed position to assume the opened position, thus providing an elevator having jaws which will be normally maintained in the closed position by the weight of a rod or the like supported thereon.

Another object of the invention is to provide such a sucker rod elevator having horizontally pivoted jaws with means whereby the pressure of a rod entering the elevator will assist in moving the jaws to the opened position.

Another object of the present invention is to provide an elevator having horizontally pivoted jaws with means independent of the weight of the rod tending to yieldingly maintain the jaws in the closed position and to provide a simple and efficient means for pivoting the jaws to the opened position.

Another object of the invention is to provide an elevator with a latch to maintain the jaws in a closed position, and to provide a latch and opening mechanism for an elevator by which gripping and pressing

two parts together will release the lock and move the jaws to the open position.

Various further objects and advantages of the present invention will be apparent from a description of a preferred example of a rod elevator embodying the invention. Reference is therefore made to the accompanying drawings in which the elevator is shown in its preferred form.

In the drawings:

Figure 1 is a top plan view of the rod elevator.

Fig. 2 is a side elevation partly in vertical section.

Fig. 3 is a rear elevation disclosing certain of the jaw operating mechanism, part of the sucker rod being broken to contract the view and.

Fig. 4 is front elevation of the elevator.

Referring to the drawings, the rod elevator comprises a body 2 having opposed trunnions 3—3 which provide a means whereby the body may be journalled in bearings of a bail, or the like, employed to support the elevator. The body 2 is provided with a rectangular depression or recess 4 in its upper face and with a rod receiving way 5 extending radially from the center of the elevator and preferably at right angles to the axis of the trunnions 3—3. The rod receiving way 5 is preferably tapered outwardly at the outer end of the way, as indicated at 6, to facilitate guiding a rod into the elevator.

Within the recess 4 of the body 2 are provided two movable jaws 7—7 having semi-circular meeting faces 8, which together define a vertically disposed circular closure 90 at the center of the body of the elevator, operative to close in upon a rod or like article and support the same in the elevator. The top faces of the jaws 7—7 preferably are flushed with the top of the body 2 and the front and rear walls of the jaws 7 fit the front and rear walls of the recess 4 of the body 2. The outer sides of the jaws 7 are spaced somewhat from the end walls of the recess 4 so that the outer side walls of the jaws 7 are free to pivot downwardly in the elevator to position the meeting faces upward in the open position.

Parallel shafts 9—9 extend horizontally

through the jaws 7-7 being journalled in the body 2, and disposed transversely to the axis of the trunnions 3-3. Pins 10-10 extend vertically through the jaws 7-7 and 5 shafts 9-9 to key the jaws 7 to the shafts 9.

The bottom walls of the jaws 7-7 are partially cylindrical in shape at their lower outer ends as indicated at 11-11, to permit the meeting faces 8-8 of the jaws to pivot 10 upwardly with the shafts 9-9 in moving the jaws to an opened position, and inner ends of the bottom walls of the jaws 7-7 are adapted to engage the bottom of the recess 4 as at points 12-12 between the shafts 15 9-9 so that the jaws 7-7 are supported by the body 2 from pivoting downwardly beyond the closed position.

Preferably means are provided so that the pressure of rod or the like entering the elevator will assist in moving the jaws 7-7 to the opened position. Such means are provided by front walls 13-13 of the jaws 7-7 which converge inwardly from the front side of the recess 4 at the top of the jaws 25 7-7 and there below are cut backward as indicated at 14-14. It can thus be seen that the pressure of a rod or the like attempting to enter the rod receiving way 5 against the walls 13-13 tend to spread the jaws 7-7 apart and also to force the meeting faces of the jaws upward, with the result that such jaws 7-7 will tend to move upwardly under the pressure of the rod entering the receiving way 5 to admit the rod therein.

Means are provided in the elevator normally tending to yieldingly maintain the jaws 7-7 in the closed position, such means being provided by a tension spring 15 attached at its ends to vertical arms 16-16 40 extending upward from the rear ends of the shafts 9-9, the spring 15 thus applying a tension normally urging the shafts 9-9 to pivot into the closed position. In order to open the jaws 7-7 and release a rod or the like held therein, the shafts 9-9 are provided with opposed pins 17-17 normally extending horizontally outward from the ends of the shafts 9-9. Such pins 17-17 are both engaged by a U-shaped operating lever 18 providing a horizontal operating bar or handle 19 at the rear of the body. The operating lever 18 has arms 20-20 pivotally mounting the lever on pins 21-21 supported by ears 22-22, which extend

55 rearwardly from the body 2 of the elevator and beyond the pins 21, the arms 20-20 extend above and contact with pins 17-17 as indicated at 23-23. To open the jaws 7-7, the bar 19 of the lever 18 is pivoted 60 upwardly, thereby the lever 18 presses the pins 17-17 simultaneously downward pivoting the shafts 9-9 in the direction tending to open the jaws 7-7. The ears 22-22 are preferably provided with flat shoulders 24-24, which engage flat faces on the lever 18

to hold the ends 23 of the lever 18 against the pins 17-17 in the jaw closed position. 25 indicates an extension of the body 2 below the lever and parts operated thereby which acts as a guard to prevent articles 70 striking the lever or parts from below.

The body is provided with a rearward extension or hood 26 which extends over certain parts of the elevator to prevent articles striking the elevator mechanism from above. 75 Pins 27 are screwed into opposed sides of the hood 26 and provide a pivot mounting for a U-shaped member 28 having lugs 29-29 fitting between the outer walls of the recess 4 and jaws 7-7 to lock the jaws in the closed position. The rear bar or handle 29 of such lock mechanism is disposed above the bar or handle 19 of the jaw opening lever 18 so that the handles 29 and 19 may be simultaneously gripped together to release the jaws 7-7 and to pivot the same to the open position. Tension springs 30 normally urge the member 28 to the locking position.

90 In operation to engage a rod in the elevator, the lock member 28 is pivoted out of contact with the jaws 7-7. The elevator is then pressed against the rod, the rod entering the rod receiving way 5 and contacting with walls 13-13 of the jaws 7-7 to automatically pivot the jaws to the open position to permit the rod to enter the circular closure formed by the semi-circular meeting faces 8-8, the spring 15 yielding during this operation. When the rod is within the circular closure, the spring 15 automatically closes the jaws 7-7 around the rod and the rod may then be handled in the elevator. The force of the rod, or parts supported upon the rod will, in operation, be applied to the jaws 7-7 in a manner tending to maintain the jaws 7-7 in the closed position, thus supplementing the action of the spring 15. The jaws 7-7 may 95 positively be locked in the closed position by pivoting the lock member 28 into the position shown in Figures 1 and 2. The rod is released from the jaws 7-7 by operation of the lever 18, this lever being to the rear of the opening of the rod receiving way 5, the lever 18 may be gripped both to open the jaws 7-7 and to pull the elevator away from the rod.

100 While the elevator herein described is well suited for accomplishing the purposes of this invention, various modifications may be made in the details of construction and arrangement of parts without departing from the spirit of the invention.

105 The invention is therefore not limited to the specific embodiment described, but is of the scope set forth in the accompanying claims:

110 We claim:

115 1. In a rod elevator, a body having a

lateral rod receiving way, and jaws having meeting faces providing a circular closure for the way, the jaws being operative by pivoting on a substantially horizontal axis.

b to and from a closed position, the jaws being mounted to pivot above their axis in moving to the open position.

2. In a rod elevator, a body having a lateral rod receiving way, means pivotally mounting the body to a supporting member and jaws having meeting faces providing a circular closure for the way, the jaws being operative by pivoting on substantially horizontal axis to and from a closed position, the jaws being operated to pivot upward above their horizontal axis in moving from the closed position.

3. In a rod elevator, a body having a radial rod receiving way, jaws pivoted on horizontal shafts journalled in the body, said jaws being disposed to move upwardly above their axis in moving to the open position, and means for normally maintaining the jaws in a closed position.

25 4. In a rod elevator, a body having a rod receiving way, jaws having meeting faces providing a circular closure for the way, horizontal shafts pivotally mounting the jaws, means normally yieldingly maintaining the jaws in the closed position, and means operative by pressure of a rod entering the way to open the jaws.

35 5. In a rod elevator, a body having opposed trunnions adapted to pivotally mount the body upon a supporting member, a rod receiving way in the body, jaws having meeting faces providing a closure for the way, the jaws being mounted on the body to pivot about a horizontal axis in moving to and from the closed position, means for jointly actuating the jaws to the opened position, means yieldingly maintaining the jaws in the closed position, and means automatically opening the jaws on insertion of a rod into the way.

50 6. A rod elevator comprising a body, a recess in its upper face, a radially extending rod receiving way in the body, jaws in the recess providing a closure for the way, the jaws being mounted to pivot on the horizontal axis to and from the closed position, the jaws having faces operative to automatically open the jaws on an insertion of a rod into the way, means for normally maintaining the jaws in the closed position, and means for opening the jaws.

60 7. An elevator of the class described, comprising a body having a rod receiving way, jaws providing a closure for the way, means for pivotally mounting the jaws to pivot about a substantially horizontal axis in moving to and from the closed position, the meeting faces of the jaws moving upwardly in assuming the opened position, a pivotally mounted lever operative to simultaneously

open the jaws, and spring means normally maintaining the jaws in the closed position.

8. In an elevator of the class described, the combination with a body having a rod receiving way and opposed trunnions, jaws having meeting faces providing a closure for the way, means for pivoting the meeting faces of the jaws upwardly about a horizontal axis in moving the jaws to an open position, and means for opening the jaws, and means for closing the jaws. 70 75

9. A rod elevator of the class described comprising a body having a rod receiving way, horizontally pivoted jaws having meeting faces providing a closure for the way, the meeting faces of the jaws moving upwardly in assuming the open position, means on the jaw to automatically open the same when a rod is inserted in the way, a pivotally mounted lever operative to jointly actuate the jaws to the opened position, and a spring normally maintaining the jaws in the closed position. 80 85

10. In a rod elevator, the combination of a body having a rod receiving way, jaws having meeting faces providing a closure for the way, means pivotally mounting the jaws to pivot on a substantially horizontal axis in moving to and from the closed position, means normally maintaining the jaws in the closed position, a lever for jointly actuating the jaws to the open position, means on the jaws to automatically open the jaws upon an insertion of a rod into the way, and a lock operative to positively lock the jaws in the closed position. 90 95 100

11. In a rod elevator, a body having a lateral rod receiving way, and jaws having rod gripping faces, the jaws being operative by pivoting on a substantially horizontal axis to and from the closed position, the jaws being arranged to pivot in a direction opposed to the weight of a rod received, in assuming an open position. 105

12. In a rod elevator, a body having a lateral rod receiving way, jaws operative by pivoting on a substantially horizontal axis to and from a closed position, the jaws being arranged to bear against the body in load receiving position, whereby at least part of the weight of the load may be transferred directly from the jaws to the body.

ferred directly from the jaws to the body. 120
13. In a rod elevator, a body having a lateral rod receiving way, jaws operative by pivoting on a substantially horizontal axis to assume load receiving and load releasing positions, the jaws contacting with the body in work receiving position to transfer at least part of the load of the work directly thereto, the movement of the jaws towards the work releasing position being opposed 125 by the weight of the work.

14. In an elevator of the class described, a body having a lateral rod receiving way, jaws operative by pivoting on a substantially 130

horizontal axis to and from a work engaging position, the jaws contacting with the body to directly transfer at least part of the weight of the work thereto in working engaging position, the jaws being arranged to move in a direction opposed to the weight of the work in assuming a work releasing position, means for opening the jaws, and means for locking the jaws in work engaging position.

15. In an elevator of the class described, a body having a lateral rod-receiving way, jaws mounted on the body operative by pivoting on a substantially horizontal axis

to and from a work engaging position, said jaws contacting with the body in the work engaging position to effect direct transfer of at least part of the weight of the work thereto, the jaws being arranged to pivot in a direction opposed to the weight of the work in assuming a work releasing position, means actuating the jaws to work releasing position, and means for locking the jaws in work engaging position.

Signed at Los Angeles, Calif., this 3rd day of June, 1924.

WILLIAM P. SCHLINGER.
GEORGE R. PARANTEAU.
